(57) **CLAIM**

The ornamental design for a gyratory crusher frame, as shown and described.

DESCRIPTION

FIG. 1 is a perspective view of a first embodiment of a gyratory crusher frame;

FIG. 2 is a bottom view thereof;

FIG. 3 is a top view thereof;

FIG. 4 is a front view thereof, wherein the rear view corresponds thereto; and

FIG. 5 is one side view thereof, wherein the other side view corresponds thereto.

FIG. 6 is a perspective view of a second embodiment of a gyratory crusher frame;

FIG. 7 is a bottom view thereof;

FIG. 8 is a top view thereof;

FIG. 9 is a front view thereof wherein the rear view corresponds thereto; and;

FIG. 10 is one side view thereof, wherein the other side view corresponds thereto.

FIG. 11 is a perspective view of a third embodiment of a gyratory crusher frame;

FIG. 12 is a bottom view thereof;

FIG. 13 is a top view thereof;

FIG. 14 is a front view thereof wherein the rear view corresponds thereto; and,

FIG. 15 is one side view thereof, wherein the other side view corresponds thereto.

The broken lines in the drawings depict unclaimed environmental subject matter.
